JOSEPH VON DEN DRIESCH, OF DRESDEN, GERMANY, ASSIGNOR TO THE FIRM FR. KÜTTNER AKTIENGESELLSCHAFT, OF PIRNA-ON-THE-ELBE, GERMANY

APPARATUS FOR WASHING, BLEACHING, AND DYEING ARTIFICIAL SILK IN HANKS OR SPINNING CAKES

Application filed May 8, 1928, Serial No. 276,133, and in Germany April 16, 1927.

This invention relates to the washing, bleaching and dyeing of artificial silk fibres in the form of hanks, as delivered by the reels, and more particularly of artificial silk in the form of spinning cakes, as taken from the spinning cans of the spinning centrifuges in the form of so to speak annular or coreless cross-wound bobbins.

The object of the invention is to subject fibres in these forms in large quantities to the action of the treatment liquid acting as uniformly as possible upon all parts of the lot with the simplest possible manipulation, and satisfactory utilization of the treatment liquid, and at the same time absolutely to prevent the hank-like or annular form of the fibres from being lost and to prevent the fibres themselves from becoming entangled.

The present invention seeks to attain this object by employing cages or hurdles adapted to be stacked one above the other, the hanks or spinning cakes being laid flat upon the grid-like bottoms thereof in a simple layer side by side close together, so that the bottom is covered as completely as possible. The internal depth between the bottom and the top of the cage or between two superposed gratings should amount to but little more than the actual thickness of the insertion, so that the fibrous structure can rise and loosen somewhat under the action of its buoyancy, without losing its form. The flow of the treatment liquid may also tend to raise or lower the fibrous structures if the velocity of flow is made sufficiently great, the direction of flow being in that case preferably changed from time to time. In any case the treatment liquid is caused to flow in a vertical direction through the cages or hurdles stacked one above the other. If for the purpose of facilitating manipulation or for the purpose of having a larger quantity of liquid between each two gratings, the cages or hurdles are made higher than corresponds to the condition just considered, special holders should be provided, which restrict the freedom of movement of the fibrous structures to the appropriate limit. The individual receptacles for the layers of fibrous structures are to be de-

scribed as cages if they have covers of their own. It is of course preferable to construct them as hurdles without such covers, which are replaced by the grid bottoms of the next hurdles above. The entire stack then only requires one covering.

In the accompanying drawings,

Figs. 1 and 2 illustrate one constructional form, which is designed for the successive treatment of small separate lots with different treatment liquids. The lots are lodged in troughs a^1 , a^2 , a^3 and so forth, which can be conveniently handled by means of rods b , and in particular can be placed upon and moved along a framework c , for the purpose of bringing them successively underneath the spraying nozzles d^1 , d^2 , d^3 and so forth, which deliver different treatment liquids, such as chemically active baths alternating with rinsing water. The liquids traversing the troughs escape through cocks e into funnels f^1 , f^2 , f^3 and so forth having pipes connected with them, which convey the liquids away into collecting or reviving tanks. In the troughs can be placed the hurdles, which consist of grid bottoms g and rim-like frames h . Upon the grid bottoms are laid the flattened spinning cakes z , in such a way that they are in close contact with one another and cover the grid bottom as completely as possible, so as to constrain the liquid to pass through the layers of fibres. Since the frames h are of greater depth than corresponds to the condition just discussed, the spinning cakes inserted therein are held down by thick perforated strips i of celluloid, the ends of which are inserted in suitable recesses in the border frames h and which can be withdrawn by bending them. The grooves h' in the border frames enable the hurdles to be conveniently manipulated by engaging the tips of the fingers of the hand extending over the margin of the border frame in the said grooves. The perforated cover plate k is for the purpose of uniformly distributing the liquid flowing out of the spraying nozzles.

The troughs a can be saved if the border frames h are superposed with the interposition of packings.

What I claim is:—

1. In an apparatus for liquid treatment of fibrous material in the form of spinning cakes, comprising a framework, a series of spraying devices with nozzles mounted above the framework in spaced relation to each other, the alternate nozzles being adapted for delivering sprays of chemically active liquids and the intermediate nozzles for delivering rinsing liquid; a series of troughs of substantially rectangular cross-section fitting in said framework to register with the nozzles and provided with means for removably supporting them therein, a hurdle in each trough consisting of alternating grid bottoms and frames stacked on top of each other, perforated strips of flexible material adapted to be sprung into position in horizontal grooves provided therefor in opposite side walls of said frames, said hurdles being so dimensioned that the spinning cakes may be packed tightly on the bottoms between said side walls and held down by said strips, thereby providing space between each layer of said cakes and the next bottom.
2. In an apparatus as described in claim 1, a perforated cover fitting snugly in each of said troughs and resting on said frame, draining means on each of the troughs and receptacles adapted to receive the different liquids separately from the respective draining means, the individual nozzles of the series of spraying devices being each adapted to deliver chemically active liquids, suitable respectively for washing, bleaching and dyeing treatments of the fibrous material.
3. In apparatus as described in claim 1 in which the individual nozzles of the series of spraying devices is each adapted to deliver chemically active liquids suitable for a different stage of treatment.
4. In an apparatus for liquid treatment of fibrous material in the form of spinning cakes, comprising a framework, a series of spraying nozzles mounted above the framework in spaced relation to each other, the alternate nozzles being adapted for delivering sprays of chemically active liquids and the intermediate nozzles for delivering rinsing liquid; a series of troughs fitting in said framework to register with the nozzles and provided with means for removably supporting them therein, a hurdle in each trough, perforated strips of flexible material adapted to be sprung into position in horizontal grooves provided therefor in opposite side walls of said frames, said hurdles being so dimensioned that the spinning cakes may be packed tightly on the bottoms between said side walls and held down by said strips, thereby providing space between each layer of said cakes and the next bottom.

In testimony whereof I have signed my name to this specification.

JOSEPH VON DEN DRIESCH.
